(57) **CLAIM**

The ornamental design for a cleaning pad for a mobile cleaning robot, as shown and described.

DESCRIPTION

FIG. 1 is a top-front-right-perspective view of our cleaning pad for a mobile cleaning robot with a pad assembly in a stored position;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is a bottom-front-left-perspective view thereof.

Any features shown in short-dashed lines represent stitching that are a part of the claimed design.
